UNITED STATES PATENT OFFICE.

WILLIAM E. DE VAULT, OF COLERAIN, OHIO.

EXTENSIBLE BED.

SPECIFICATION forming part of Letters Patent No. 748,847, dated January 5, 1904.

Application filed September 23, 1903. Serial No. 174,369. (No model.)

To all whom it may concern:

Be it known that I, WILLIAM E. DE VAULT, a citizen of the United States, residing at Cole-
rain, in the county of Belmont, State of Ohio,
5 have invented certain new and useful Im-
provements in Extensible Beds; and I do hereby
declare the following to be a full, clear, and
exact description of the invention, such as
will enable others skilled in the art to which
10 it appertains to make and use the same.

This invention relates to extensible bed-
steads so constructed that they may be ad-
justed to form either a single or a double bed,
the object of the invention being to provide
15 a construction which will be cheap and sim-
ple of manufacture, which will be rigid in
both positions of its adjustment, and which
may be easily and quickly manipulated.

Other objects and advantages of the inven-
20 tion will be understood from the following de-
scription.

In the drawings forming a portion of this
specification, and in which like numerals of
reference indicate similar parts in the several
25 views, Figure 1 is a perspective view show-
ing a bedstead embodying the present inven-
tion. Fig. 2 is a perspective view showing
the bedstead in closed position. Fig. 3 is a
30 horizontal section through the headboard
with the bedstead in extended position. Fig.
4 is a detail view of the folding brace at one
end of the bedstead.

Referring now to the drawings, there is
shown a bedstead comprising a headboard
35 and a footboard, to which are connected side
rails, which latter support slats in combina-
tion with a supplemental middle rail. The
headboard comprises the two posts 5 and 6,
to which are connected in the usual manner
40 the side rails 7 and 8, the latter being con-
nected also to the posts 9 and 10 of the foot-
board. The head and foot boards are similar
in construction, so that a description of one
will suffice for both. One post, which is the
45 post 6 of the headboard, and the post 10 of
the footboard, has attached thereto one mem-
ber of the board consisting of spaced plates
or planks 11 and 12, between which is re-
ceived the single plate or plank 13 of the op-
50 posite post, the plate or plank 13 being adapt-
ed to slide freely between the plates or planks

11 and 12, so that the posts of each board
may be moved toward or away from each other
to reduce or increase the aggregate width of
the board, there being between the plates or 55
planks 11 and 12 a pocket 14, as illustrated.

Connecting the lower edges of the plates or
planks 11 and 12 of the headboard with the
corresponding plates or planks of the foot-
board are supplemental or intermediate rails 60
15 and 16, which extend longitudinally of the
bedstead and which are designed to receive
and support slats 17 and 18 in connection
with the side rails 8 and 7, respectively, when
the bedstead is reduced in width, while the 65
inner ends of the slats 18 are supported by
the rail 16 when the bed is extended. The
supplemental rail 16 has a supporting leg 19
at its middle point. As the side rails 7 and
8 are moved toward and away from each other 70
the slats 18 slide transversely of the upper
face of the supplemental rail 16.

Each of the corner-posts of the bedstead is
provided with ears 20, and to the ears of the
posts of the headboard are pivoted the brace 75
members 21 and 22, which are connected at
their opposite ends by means of a hinge 23,
the mutually adjacent extremities of the
members 21 and 22 being beveled transversely,
so that said members will not aline, but will 80
lie at a broad angle to each other when the
sides of the bedstead are drawn outwardly to
their limit, and when the sides are pressed
toward each other the members will readily
fold. These members serve to limit the ex- 85
tension of the bedstead, there being similar
members designated by the same reference-
numerals employed in connection with the
footboard.

It will be understood that in practice modi- 90
fications of the specific construction shown
may be made and that any suitable materials
and proportions may be used for the various
parts without departing from the spirit of the
invention.

95
What is claimed is—

An extensible bedstead comprising tele-
scopic head and foot boards and connected
side rails, supplemental longitudinal rails
connected to corresponding head and foot 100
board members at one side of the bedstead,
a supporting-leg for one of said supplemental

rails and slat-sections carried by the side rails and resting upon the supplemental rails, the head and foot boards comprising posts, folding stops connected to the posts of each board, said stops comprising hinged sections, and means for preventing alinement of the sections.

In testimony whereof I affix my signature in presence of two witnesses.

WM. E. DE VAULT.
